UNITED STATES PATENT OFFICE.

JOHN GRIFFITH HARVEY, OF CHICAGO, ILLINOIS, ASSIGNOR TO AMERICAN STOVE COMPANY, OF ST. LOUIS, MISSOURI, A CORPORATION OF NEW JERSEY.

DESIGN FOR A TOP-PLATE AND OVEN FOR GAS-STOVES.

40,690.

Specification for Design.

Patented May 10, 1910.

Application filed July 21, 1909. Serial No. 508,846. Term of patent 14 years.

To all whom it may concern:

Be it known that I, JOHN G. HARVEY, a citizen of the United States, residing at Chicago, in the county of Cook and State of Illinois, have invented a new, original, and ornamental design for a Top-Plate and Oven for Gas-Stoves, of which the following is a specification, reference being had therein to the accompanying drawing.

The new design is shown in perspective view in the accompanying drawings.

I claim—

The ornamental design for a top plate and oven for gas stoves, as shown.

JOHN GRIFFITH HARVEY.
